MOLDED PACKAGING TRAY FOR PRODUCE OR THE LIKE

Richard F. Reifers, New Canaan, Conn., and Kenneth D. Bixler, Huntington, N.Y., assignors to Diamond International Corporation, New York, N.Y.

Filed Oct. 30, 1972, Ser. No. 301,762

Term of patent 14 years

Int. Cl. D9—03

U.S. Cl. D9—243

FIG. 1.

FIG. 2.

FIG. 3.

FIG. 4.

FIG. 5.

FIG. 6.

FIG. 7.

FIG. 8.

FIG. 1 is a top plan view of a molded packaging tray for produce or the like showing our new design;

FIG. 2 is a bottom plan view;

FIG. 3 is a side elevational view; and

FIG. 4 is an end elevational view thereof;

FIG. 5 is a view similar to FIG. 1 but showing a modified form of our new design;

FIG. 6 is a bottom plan view;

FIG. 7 is a side elevational view; and

FIG. 8 is an end elevational view thereof.

The characteristic feature of the design resides in the upright U- or V-shaped ribs forming the open-window bottom in combination with a peripheral U- or V-shaped boundary rib which extends completely around the bottom portion to form a transition zone with the long side walls and the short end walls, the boundary rib below the long side walls comprising a downward extension of such side walls, as shown.

We claim:

The ornamental design for a molded packaging tray for produce or the like, as shown and described.
